UNITED STATES PATENT OFFICE

2,001,695

OSCILLATOR CIRCUIT

Paul O. Farnham, Beonton, N. J., assignor, by
mesne assignments, to Radio Corporation of
America, New York, N. Y., a corporation of
Delaware

Application January 8, 1932, Serial No. 585,592
Renewed March 16, 1934

8 Claims. (Cl. 250—20)

This invention relates to oscillator circuits and more particularly to tuned oscillator circuits which will automatically deliver higher voltages as the oscillator is tuned to lower frequencies.

5 My copending application, Ser. No. 564,676, filed September 23, 1931, describes and claims oscillator circuits of this general type which, when incorporated in a superheterodyne receiver, tend to reduce those variations in audio output that arise from the decreased transmission of the lower carrier frequencies. The present invention relates to other circuit arrangements for effecting the desired variation, with frequency, of the oscillator output voltage.

10 It is possible to design an oscillator circuit and a signal frequency circuit which exhibit a substantially constant frequency difference when tuned by similar sections of a gang condenser. To obtain this effect, the inductance of the oscillator circuit is made substantially less than that of the signal frequency circuit, and a lagging condenser having a capacity several times that of the tuning condenser is included as a series element of the oscillator circuit. As the gang condenser is adjusted for tuning, the presence of the series condenser in the tuned circuit of the oscillator makes the value of the total capacity tuning the oscillator coil lag behind the value of the capacity tuning the radio frequency circuits, and the series condenser which thus makes it possible to employ a single tuning control in superheterodyne receivers will therefore be designated, in the following specification and claims, as the lagging condenser. The oscillator circuits contemplated by the present invention are of this type and the desired frequency variation of the oscillator output voltage is obtained by coupling another circuit of the oscillator across the series lagging impedance of the resonant circuit.

An object of the invention is to provide an oscillator including a resonant circuit of the type including a series lagging condenser, and in which another circuit of said oscillator is coupled across the series lagging condenser. Another object of the invention is to provide an oscillator including a tuned grid circuit including a series lagging condenser, and in which the instantaneous alternating voltage on the plate is substantially equal to that developed across the lagging condenser.

These and other objects and advantages of the invention will be apparent from the following specification, when taken with the accompanying drawing, in which,

Fig. 1 is a fragmentary circuit diagram of a superheterodyne receiver which includes an oscillator embodying the invention, and

Fig. 2 is a circuit diagram of another oscillator embodying the invention.

In the drawing, the reference numeral 1 identifies a vacuum tube for amplifying signal energy at carrier frequency, the amplified energy being passed to the detector tube 2 and there combined with local oscillations generated by oscillator tube 3 to produce a beat or intermediate frequency. With the exception of the oscillator circuits, this portion of the superheterodyne receiver may be of any appropriate design. In the typical arrangement shown in the drawing, the input circuit of the carrier amplifier comprises an inductance L and tuning condenser C, the input circuit being connected or coupled in any appropriate manner to the antenna or collecting structure AG.

The plate circuit of amplifier 1 is coupled to the detector input circuit L, C, which may be, and preferably is, substantially identical with the amplifier input circuit, the adjustable capacities being usually provided by sections of a gang condenser, as is indicated by the broken line 4 which connects the tuning condensers of the amplifier and detector stages. The beat frequency set up in the detector is passed, as by coupling transformer 5, to the intermediate frequency amplifier tube 6.

The resonant circuit of the oscillator tube 3 includes an inductance L₀, a series lagging condenser C_s and a tuning condenser C which may be, and preferably is, a section of the gang condenser employed for tuning the carrier frequency circuits. As indicated by the broken line 7, the several condensers C are mechanically connected for simultaneous adjustment. As distinguished from the customary oscillator circuits, the plate circuit is not coupled to the inductance L₀ of the grid circuit but is coupled across the series lagging condenser C_s. This coupling may comprise an inductance L₂ connected across the condenser C_s and coupled to a winding L₃ in the plate circuit with substantially unity coupling. This close coupling may be secured by employing twin windings, i. e., the inductances L₂, L₃ are wound turn for turn and closely adjacent each other on the same form. The inductances L₂, L₃ constitute twin chokes having inductances of such relatively high value as to resonate with the series capacity C_s at a frequency substantially lower than the lowest frequency within the tuning range of the oscillator.

The cathode circuit of the oscillator tube 3 includes a bias resistor 8, shunted by a condenser 9 which provides a by-pass for oscillator frequencies.

5 The oscillatory voltage developed by tube 3 is impressed on the first detector 2 by coupling to the oscillator inductance L_o in any suitable manner. As shown, a coil L_1 is coupled to L_o and included in the detector cathode circuit between 10 the cathode and the bias resistor 10 which is shunted by condenser 11. The inductance L_1 is preferably a twin winding, as above defined, extending along about one-tenth of the grid inductance L_o .

15 It will be apparent that the substantially unity coupling between windings L_2 , L_3 makes the instantaneous oscillatory voltage on the plate of tube 3 substantially identical with that established at the junction of inductance L_o and the 20 lagging condenser C_s . When the resonant circuit is tuned to higher frequencies, the impedance of the condenser C_s decreases and therefore the voltage on the plate decreases. As a result, the 25 current flow in the inductance L_o , and therefore in the output circuit, decreases at a more rapid rate than the rate of frequency increase and the current output falls off with increasing frequency.

Other methods of coupling the plate circuit across the lagging condenser C_s are possible and, 30 in Fig. 2, a capacitive coupling is illustrated. A coupling condenser 12 is connected between the plate and the junction of inductance L_o and the condenser C_s , the condenser 12 having a low impedance for oscillator frequencies. A choke 13 is included in the plate circuit connection to a 35 positive potential source which is indicated by the legend E_B . The usual grid resistance R is shunted across the lagging condenser C_s to complete a direct circuit for the application of the bias voltage to the grid.

40 Typical values of circuit constants which will give satisfactory operation in the circuit of Fig. 1 are as follows:

Tube 3=Type 227

Condenser C_s =about 3.3 times the maximum 45 value of C

Inductance L_o =about 75% of the inductance L
Resistance 10=5000 ohms

Condenser 11=0.1 microfarad

50 Resistance 8=5000 ohms

Condenser 9=1000 micromicrofarads

E_B =90 volts

55 In the circuit shown in Fig. 2, the coupling condenser 12 may be about 0.1 microfarad, and the choke 13 is an inductance of such value as to resonate with condenser C_s at a frequency below the tuning range of the oscillator.

60 It will be understood that the magnitude of condenser C_s may be varied to align the oscillator circuit to track with the carrier frequency circuits but, once aligned, the value of C_s remains fixed and the only adjustment of the oscillator circuit in the reception of signals is that provided by the variable condenser C .

65 I claim:

1. In an oscillator, the combination with a vacuum tube having plate and grid elements and a cathode; and a resonant circuit between cathode and grid comprising an inductance shunted by a 70 series lagging condenser in series with a tuning condenser; the junction of said condensers having an oscillator-frequency connection to the cathode, and the junction of the inductance and tuning condenser being connected to the grid; of means coupling the plate circuit across said se-

ries lagging condenser, said means comprises a transformer having one winding in the plate circuit and a second winding shunted across said series lagging condenser.

2. The invention as set forth in claim 1, where- 5 in the windings of said transformer resonate with said lagging condenser at a frequency substantially lower than the lowest frequency within the tuning range of said oscillator.

3. The invention as set forth in claim 1, where- 10 in the windings of said transformer are twin windings wound turn for turn on the same form and having an inductance resonating with said lagging condenser at a frequency below the tuning 15 range of said oscillator.

4. In a variable frequency oscillator adapted for the generation of voltage which increases with decreasing frequency, the combination with a tube having a cathode, a control electrode and a plate electrode, of impedance elements forming a circuit tunable over a band of frequencies and connected between said cathode and control electrode, said circuit including as a series element a composite impedance resonant to a frequency lower than the lowest frequency of said 20 band of frequencies, and means coupling said plate electrode to said composite impedance.

5. The invention as set forth in claim 4, where- 25 in said composite impedance comprises a fixed inductance shunted by a relatively fixed capacity.

6. In a variable frequency oscillator adapted for the generation of voltage which increases with decreasing frequency, the combination with a tube having a cathode, a control electrode and a plate electrode, of impedance elements forming a 35 circuit tunable over a band of frequencies and connected between said cathode and control electrode, said circuit including as a series element a fixed inductance shunted by a relatively fixed condenser, said series element being resonant to a 40 frequency below the lowest frequency of said band of frequencies, and means coupling said plate electrode to said series element, said coupling means to the series element being the sole coupling between said plate electrode and the ele- 45 ments of said tunable circuit.

7. In a variable frequency oscillator adapted for the generation of voltage which increases with decreasing frequency, the combination with a tube having a cathode, a control electrode and a plate 50 electrode, of impedance elements forming a circuit tunable over a band of frequencies and connected between said cathode and control electrode, said circuit including as a series element a fixed inductance shunted by a relatively fixed 55 condenser, said series element being resonant to a frequency below the lowest frequency of said band of frequencies, means coupling said plate electrode to said series element, and output voltage terminals coupled to a second inductance in 60 said tunable circuit.

8. In a superheterodyne receiver of the single control type, the combination of a carrier wave circuit and an oscillator circuit adapted to be tuned over approximately the same frequency 65 bands, each circuit including an inductance and a tuning condenser, the tuning condensers being substantially identical and mechanically connected for simultaneous adjustment, a lagging condenser serially connected between the inductance and tuning condenser of the oscillator circuit, said lagging condenser comprising means for maintaining a substantially constant frequency difference between the resonant frequencies of 70 said circuits as said resonant frequencies are 75

varied by adjustment of said tuning condensers, an oscillator tube having a cathode cooperating with a grid electrode and a plate electrode, a connection for maintaining the cathode and the junction of said lagging condenser and its associated tuning condenser at the same oscillator-frequency potential, circuit connections for establishing at one electrode the oscillator-frequency potential of the junction of the induc-

tance and tuning condenser of the oscillator circuit, coupling means for coupling the other electrode to the junction of the lagging condenser and the inductance of the oscillator circuit, and a first detector tube for combining carrier waves transmitted by said carrier wave circuit with the oscillatory voltage developed by said oscillator tube.
